BAKING OVEN

Clyde Kratz, Norristown, Pa., assignor to K & N Soft Pretzel Company, Inc., Norristown, Pa., a corporation of Pennsylvania

Filed Apr. 14, 1964, Ser. No. 79,496

Term of patent 14 years

(Cl. D81—10)

FIG. 1

FIG. 2

FIG. 4

The rear, not shown, is substantially plain.

I claim:

The ornamental design for a baking oven, as shown and described.
